UNITED STATES PATENT OFFICE

ERNST GEIGER, OF IRVINGTON, NEW JERSEY

GARAGE

Application filed July 26, 1928, Serial No. 295,586. Renewed March 26, 1930.

The present invention, while capable of a wide range of utility for storage purposes, finds its preferred embodiment in a "sky-scraper" or "tower" garage of the general character disclosed in my prior Patent #1,636,600 granted July 19th, 1927.

It will be recalled that in this patent I disclosed the use of endless chains of connected elevator storage cabins traveling through the orbital paths defined by spaced vertical shaftways and upper and lower connective crossways. The space between the banks of vertical shaftways was horizontally sub-divided by floors, the upper of which served as car storage floors while two of the lower ones served as car delivery and receiving floors.

A primary object of the present invention is to overcome certain inherent disadvantages of the patented construction, notably to conserve space, to provide greater volume of "live" storage space, to facilitate the expeditious reception and delivery of cars and to provide a garage building which may be profitably erected and operated on a relatively small building lot in congested districts, where property is generally too valuable to justify the building of the present type of low garages.

Space economy is effected primarily by the use of relatively small storage cabins proportioned to accommodate standard-sized cars, whereby the cross-sectional area of the shaftways and crossways may be reduced, the cabins themselves made of smaller dimensions in all directions and a greater number of cabins consequently used to make up an endless cabin chain of any given length.

A special car-hoisting and car-parking means, wholly independent of the storage cabins, is used for handling odd-sized cars, thereby eliminating the need for unduly large storage cabins, permitting odd-sized cars to be compactly arranged in the storage spaces which are provided for them, and obviating the necessity for reducing available "live" storage space in that none of the storage cabins are used as conveyor elevators for the storage or parking floors of the building.

In accordance with the present invention, the central storage floors, confined between

the banks of vertical shaftways for the cabin chains, need have no communication with such shaftways. These storage floors are supplied with odd-sized cars to be parked or stored through the intermediary of elevators of more or less conventional construction arranged at opposite ends of the storage floors and wholly exteriorly of the cabin chain shaftways and the space enclosed thereby.

The invention in effect involves the use of the patented endless cabin chain garage system in combination with a wholly independent garage system, the two systems being so interrelated and interlocked that the latter efficiently utilizes all of the waste space of the former and without in any way detracting from its efficient operation or its ability to receive and deliver large numbers of cars in a short space of time.

The building of the present invention is so designed that it is particularly well suited for the erection of sky-scraper garages on a relatively narrow lot running from street to street in the center of a block. Present building regulations which call for set-backs or terraces render it impossible to use full length cabin chains at the front and rear of such a building. With the present invention, however, the cabin chain shaftways extend the full height of the building, intermediate the ends of the latter, and the set-backs are provided in the extended ends of the supplemental storage floors of the secondary garage, where great height is not needed.

Such a building plan also promotes high efficiency of the endless chain garage and ready accessibility for motorists in that a car may enter or leave the garage from either of two streets.

With the above noted and other objects in view, the invention consists in certain novel features of construction and combinations and arrangements of parts which will be more fully hereinafter described and pointed out in the claims.

The invention may be more fully understood from the following description in connection with the accompanying drawings, wherein:

Figure 1 is a broken longitudinal vertical

sectional view through a garage embodying the invention.

Figure 2 is a transverse, vertical sectional view through the top of the garage taken approximately on the line 2—2 of Figure 1.

Figure 3 is a view complementing Figure 2, showing the lower end of the garage and taken on the same line 2—2.

Figure 4 is a broken sectional plan view taken approximately on the staggered line 4—4 of Figure 1.

Figure 5 is an enlarged sectional detail through one of the elevator platforms which convey cars to and from the storage floors, this view being taken approximately on the line 5—5 of Figure 1.

It may be noted at the outset that all of the figures of the drawings are highly diagrammatic and for the sake of clarity avoid all showing of details of the endless cabin chains and various other equipment which is disclosed in my prior patent above identified and in various copending applications.

In the drawings, I have used the reference numerals 10, 10 to designate the opposite side walls of a relatively long, narrow building, this building being provided with a basement floor 11 and a central roof section 12. The side walls 10 cooperate with transverse vertical walls 13 and longitudinal vertical walls 14 to define banks of vertical shaftways 15 at opposite sides of the building, these shaftways extending the full height of the building and being connected at their tops and bottoms by horizontal cross-ways 16 and 17. Trains of storage cabins 18 are mounted on endless chains 19 actuated in any suitable manner (not shown) for movement through the orbital paths defined by the vertical shaftways 15 and the upper and lower cross-ways 16 and 17.

As thus far described, the construction may be entirely conventional and in accordance with my prior patent. An improvement over such patent, however, resides in the use of a series of horizontal storage floors 20, the restricted intermediate portions of which are disposed between the banks of shaftways 15. These floors instead of terminating at the ends of the shaftway banks, as in my prior patent, extend therebeyond, such floor extensions being numbered 21 and being the full width of the building. In order to comply with building requirements, terraces or set-backs such as 22 and 23 are provided by cutting down or stepping back certain of the upper storage floor extensions 21. In this manner building laws are complied with without the need for reducing the total height of any of the shaftway units 15, 16 and 17.

Preferably the lowermost of the floors between the shaftways 15 comprises a receiving floor 24 while the immediately superjacent floor 25 serves as a car delivery floor.

Floors 24 and 25 at their ends communicate by ramps 24a and 25a with common driveways 26 at opposite ends of the building, which driveways communicate with the two streets on which the ends of the building front. Preferably control rooms, or control houses 27 are mounted between the ramps 24a and 25a and permit business to be conveniently transacted with the drivers of cars either when entering or leaving the garage.

Vertical shaftways 28 and 29 are provided in diagonally opposite corners of the building accommodating vertically movable elevators or hoisting platforms 30 of more or less conventional general design. These platforms or elevator cars may be operated by cables or plungers in any well-known manner and are used for transporting cars to and delivering cars from the storage floors 20 and the storage floor extensions 21.

Each shaftway 28, 29 at the ground floor of the building is provided with an entrance doorway 32 in one and through which a car may be driven from the street directly on to the elevator platform 30. The shaftway doorways which communicate with the various storage floor extensions 21, however, are not aligned with the doorways 32 but comprise relatively elongated openings 33 provided in the inner sides of the shaftways and extending from the innermost corners thereof. This arrangement of elevator doorways and shaftways 28 and 29 together with a special car-handling mechanism mounted on the platforms 30 facilitates the convenient handling of cars at the storage floors. Preferably a pivotally mounted skeleton platform 34 is arranged on each of the platforms 30. This platform is axially centered with the elongated platform 30 as shown at the left-hand corner of Figure 4 at the time when the car is driven in through the doorway 32. It consists preferably of a pair of parallel rails 35 connected by cross-braces 36 and 37. One of the braces 37 has a pivotal connection at 38 with the platform 30 and the other cross-brace 36 carries a roller 40 travelling on a bearing plate 40 on the platform 30.

By virtue of this arrangement, when one of the elevators 30 reaches a storage floor extension 21, the swinging skeleton platform 34 may be manually or otherwise drawn partially through the doorway 33 as seen at the upper right hand corner of Figure 4, so that a car without turning the wheels may be driven straight out as indicated by the arrow in Figure 4 and driven into any of the numerous parking places shown diagrammatically at 41. Subsequently skeleton platform 25 is pushed back into the elevator to clear the storage floor and permit the elevator to again travel in its shaftway. In Figure 4 elevator shaftway 29 accommodates a receiving elevator 30 which carries odd-sized cars to the storage floors and the shaftway 28

accommodates the delivery elevator 30 which receives cars from the storage floors and delivers them through the shaftway door 32.

From the foregoing description it will be seen that I have shown in effect two independent garage systems, each of which may operate wholly independently of the other and yet which are so mechanically interrelated and physically interlocked that one system utilizes all of the waste space of the other and permits the economical erection of skyscraper garages on relatively narrow and valuable plots of land.

The secondary garage system materially reduces the cost of the equipment for and effects space economy in the endless cabin chain system, in that the secondary system takes care of all odd-sized and unduly large cars, relieves the live storage space cabins of the endless chains from elevator duty, permits smaller storage cabins to be used with more cabins in a given length of chain, and provides means for effectively taking care of an overflow of standard sized cars in an emergency.

The special type of pivoting car platform shown in connection with the elevators 30 may have a wide range of utility independent of its usefulness in the present organization.

The illustrated garage building, if vertically transversely bisected, would constitute two separate garages embodying the invention. Either of these garages might be used on a relatively shallow lot and be formed with a straight back wall and a terraced front. The particular number of elevators used to serve the parking floors of such garages is, of course, a matter to be determined in each individual instance and may range from one to any desired number.

Various changes and alterations might be made in the general form and arrangement of the parts described without departing either from the spirit of the invention or the scope of the appended claims.

I claim:

1. A pair of interlocking and independently operating car storage systems housed within a single building, one of said systems including spaced banks of vertical shaftways connected at their upper and lower ends by horizontal cross-ways, and endless chains of car storage cabins traveling through the orbital pathways defined by said shaftways and crossways, the other of said systems including car storage floors occupying the space between the shaftway banks and elevator means independent of the storage cabins for conveying cars thereto.

2. A pair of interlocking and independently operating car storage systems housed within a single building, one of said systems including spaced banks of vertical shaftways connected at their upper and lower ends by

horizontal cross-ways, and endless chains of car storage cabins traveling through the orbital pathways defined by said shaftways and crossways, the other of said systems including car storage floors occupying the space between the shaftway banks and elevator means, independent of the storage cabins for conveying cars to the ends of said floors, each system including means whereby cars may be loaded on and unloaded from its elevators and said means being wholly independent of each other.

3. A pair of interlocking and independently operating car storage systems housed within a single building, one of said systems including spaced banks of vertical shaftways connected at their upper and lower ends by horizontal cross-ways, and endless chains of car storage cabins traveling through the orbital pathways defined by said shaftways and crossways, the other of said systems including car storage floors occupying the space between the shaftway banks and elevators arranged at the ends of said floors for conveying cars thereto, the storage cabin system including a loading floor arranged between the shaftway banks beneath the storage floors of the other system and driveways leading from said floor to the street.

4. A pair of interlocking and independently operating car storage systems housed within a single building, one of said systems including spaced banks of vertical shaftways connected at their upper and lower ends by horizontal cross-ways, and endless chains of car storage cabins traveling through the orbital pathways defined by said shaftways and crossways, the other of said systems including car storage floors occupying the space between the shaftway banks and elevators arranged at the ends of said floors for conveying cars thereto, the storage cabin system including a loading floor arranged between the shaftway banks beneath the storage floors of the other system and driveways leading from said floor to the street, the elevator shaftway of the second system having doorways therein at street level communicating directly with the street.

5. A garage building including banks of vertical shaftways at opposite sides thereof, upper and lower transverse cross-ways connecting pairs of opposite shaftways, storage floors disposed between the banks of shaftways, an elevator shaftway at the ends of the building, a vertically movable conveyor elevator therein adapted to convey cars to and from the storage floors, endless chains of car storage cabins mounted to travel in the orbital pathways defined by the first mentioned shaftways and crossways.

6. A garage building including banks of vertical shaftways at opposite sides thereof, upper and lower transverse cross-ways, connecting pairs of opposite shaftways at their

- tops and bottoms, storage floors disposed between the banks of shaftways and extending longitudinally therebeyond, elevator shaftways adjacent opposite ends of the building,
- 5 vertically movable conveyor elevators therein adapted to convey cars to and from the ends of the storage floors, endless chains of car storage cabins mounted to travel in the orbital pathways defined by the first mentioned shaftways and cross-ways, and superimposed car receiving and delivery floors for the storage cabins disposed in the space between the shaftway banks and below the storage floors,
- 10 7. A garage building including banks of vertical shaftways at opposite sides thereof, upper and lower transverse cross-ways connecting pairs of opposite shaftways at their tops and bottoms, storage floors disposed between the banks of shaftways and extending longitudinally therebeyond, other elevator shaftways adjacent opposite ends of the building, vertically movable conveyor elevators therein adapted to convey cars to and from the ends of the storage floors, endless chains of car storage cabins mounted to travel in the orbital pathways defined by the first mentioned shaftways and cross-ways, car receiving and delivery floors for the storage cabins disposed in the space between the shaftway banks and below the storage floors, driveways communicating with the receiving and delivery floors through one end of the building, the shaftways of the conveyor elevators having doorways therein communicating directly with the street.
- 15 8. A garage building including banks of vertical shaftways at opposite sides thereof, upper and lower transverse crossways, connecting pairs of opposite shaftways at their tops and bottoms, storage floors disposed between the banks of shaftways, other elevator shaftways adjacent the ends of the building, vertically movable conveyor elevators therein adapted to convey cars to and from the storage floors, endless chains of car storage cabins mounted to travel in the orbital pathways defined by the first mentioned shaftways and crossways, superimposed car receiving and delivery floors for the storage cabins disposed in the space between the shaftway banks and below the storage floors, driveways communicating with the receiving and delivery floors through one end of the building, and means independent of said driveways for loading and unloading the conveyor elevators.
- 20 9. A garage building including banks of vertical shaftways at opposite sides thereof, upper and lower transverse cross-ways, connecting pairs of opposite shaftways at their tops and bottoms, storage floors disposed between the banks of shaftways, other elevator shaftways adjacent the opposite ends of the building, vertically movable conveyor elevators therein adapted to convey cars to and from the ends of the storage floors, endless chains of car storage cabins mounted to travel in the orbital pathways defined by the first mentioned shaftways and crossways, car receiving and delivery floors for the storage cabins disposed in the space between the shaftway banks and below the storage floors, driveways communicating with the receiving and delivery floors through one end of the building, the shaftways of the conveyor elevators having doorways therein communicating directly with the street.
- 25 10. A garage building including banks of vertical shaftways at opposite sides thereof, upper and lower transverse cross-ways, connecting pairs of opposite shaftways at their tops and bottoms, storage floors disposed between the banks of shaftways and extending longitudinally therebeyond, elevator shaftways adjacent the opposite ends of the building, conveyor elevators therein adapted to convey cars to and from the ends of the storage floors, endless chains of car storage cabins mounted to travel in the orbital pathways defined by the first mentioned shaftways and crossways, car receiving and delivery floors for the storage cabins disposed in the space between the shaftway banks and below the storage floors, driveways communicating with the receiving and delivery floors through one end of the building, the shaftways of the conveyor elevators having doorways therein communicating directly with the street.
- 30 11. A relatively long narrow building of substantial height and a pair of independently operating interlocking car storage systems housed therein, one of said systems including endless chains of car storage cabins, shaftways at opposite sides of the building spaced from the ends thereof and horizontal cross-ways at the top and bottom of the building connecting said shaftways, said shaftways and crossways defining an orbital path for the travel of the cabins of the endless chains, the other system including storage floors, the restricted intermediate portions of which are disposed between the banks of shaftways and the ends of which extend the full width of the building, and conveyor elevators disposed at the ends of the building beyond the storage cabin shaftways for delivering and receiving cars from the storage floors.
- 35 12. A relatively long, narrow building of substantial height and a pair of independently operating interlocking car storage systems housed therein, one of said systems including endless chains of car storage cabins, shaftways at opposite sides of the building spaced from the ends thereof and horizontal cross-ways at the top and bottom of the building connecting said shaftways, said shaftways and cross-ways defining an orbital path of travel for the cabins of the endless chains, the other system including storage floors, the intermediate portions of which are disposed between the banks of shaftways and the ends of which extend the full width of the building.

ing, conveyor elevators disposed at the ends of the building beyond the storage cabin shaftways for delivering and receiving cars from the storage floors, superimposed loading and 5 unloading floors for the storage cabin system arranged between the banks of shaftways and beneath the storage floors, said loading and unloading floors communicating by driveways with the street through one end of the 10 building.

13. An elevator car including a floor longer in one horizontal dimension than in the other, a track unit swivelly mounted adjacent one end on the floor, the car having a doorway in 15 one end thereof whereby a vehicle may be rolled on to the track unit through such door when the track unit is axially alined with the floor of the car, said car also having an elongated doorway in one side thereof whereby a 20 vehicle may be rolled off the track unit after the latter has been swung on its swivel bearing to a position where it projects through and beyond the said doorway.

14. A relatively long, narrow building of 25 substantial height and a pair of independently operating interlocking car storage systems housed therein, one of said systems including endless chains of car storage cabins, shaftways at opposite sides of the building 30 spaced from the ends thereof and horizontal cross-ways at the top and bottom of the building connecting said shaftways, said shaftways and crossways defining an orbital path of travel for the cabins of the endless 35 chains, the other system including storage floors, the intermediate portions of which extend the full width of the building, conveyor elevators disposed at the ends of the building beyond the storage cabin shaftways, for 40 delivering and receiving cars from the storage floors, superimposed loading and unloading floors for the storage cabin system arranged between the banks of shaftways and beneath the storage floors, said loading and unloading 45 floors communicating by driveways with the street through one end of the building, the shaftways for the conveyor elevators of the second system having doorways therein at street level communicating directly with the 50 outside of the building.

15. A pair of independently operating car storage systems housed within a single building and inter-fitting with each other, one system including endless trains of car storage 55 cabins, the other system including storage floors and an elevator for feeding cars to said floors.

Signed at New York in the county of New York and State of New York this 24th day 60 of July A. D. 1928.

ERNST GEIGER.
